UNITED STATES PATENT OFFICE

SAMUEL DANIELS, OF HARDWICK, VERMONT, ASSIGNOR TO SAM DANIELS MFG., INC., OF HARDWICK, VERMONT, A CORPORATION OF VERMONT

FURNACE

Application filed January 19, 1929. Serial No. 333,587.

This invention relates to improvements in furnaces and more particularly it relates to hot air heating plants.

An object of the invention is the provision of a furnace structure which may be readily assembled in a minimum time and is of simple design.

Another object is to provide a furnace structure in which the casing may be erected first and the furnace unit can be slidably inserted therein afterwards, thus enabling the rapid setting up of the furnace, as it is unnecessary to substantially delay the setting up of the furnace during the drying of the cement foundation.

A further object is the provision of a sectional casing having readily removable panels for access to the interior thereof and for ready removal of the furnace unit therefrom.

Another object is the provision of a novel form of furnace structure including a novel self-sustaining casing and a novel furnace unit removably disposed therein.

These and many other objects I attain by the construction shown in the accompanying drawings wherein for the purpose of illustration is shown a preferred embodiment of my invention and wherein:

Fig. 1 is a front elevation of my furnace structure with the parts assembled.

Fig. 2 is a rear view of the same.

Fig. 3 is a side view of the furnace structure.

Fig. 4 is a front elevation of the supporting base.

Fig. 5 is a plan view of the base.

Fig. 6 is a side sectional elevation substantially on line 6—6 of Fig. 1.

Fig. 7 is a fragmentary sectional view substantially on line 7—7 of Fig. 1.

Fig. 8 is a front sectional elevation substantially on line 8—8 of Fig. 6.

Fig. 9 is a sectional plan view taken substantially on line 9—9 of Fig. 1.

Fig. 10 is a section on line 10—10, Fig. 8, showing the hot air pipe, the register, and short pipe attached thereto.

Fig. 11 is a top plan view of one side assembly and a portion of the rear wall and

a portion of one of the front panels showing the grooves to receive the top section.

Fig. 12 is a bottom plan view of the top section.

Fig. 13 is a section on the line 13—13 of Fig. 6, showing the smoke pipe connection.

Fig. 14 is a section on the line 14—14 of Fig. 6.

Fig. 15 is a rear view of the feed tube.

Fig. 16 is a view of the feed tube collar. 60

Fig. 17 is a rear view of one of the removable side panels for the front showing the water pan connected therewith.

Fig. 18 is a section on line 18—18 of Fig. 17.

Fig. 19 is a section on line 19—19 of Fig. 17. 65

Fig. 20 is a view of the removable top panel of the front.

Fig. 21 is a section on the line 21—21 of Fig. 20.

Fig. 22 is a view of a modified form of pit-70 less furnace structure embodying the removable three panel front and other features of the invention.

The interlocking flanged connections between the various parts of the furnace casing 75 are somewhat exaggerated for the sake of clearness of disclosure, as the exact structure of these connections combines great rigidity with each of assembly.

In the drawings, 45 represents the side walls of the furnace casing D, which provides therein a hot air outlet and an unheated air inlet. A rear wall comprising a back 55 made of double sheet metal with a central air space and end panels 44, joins the side walls 45. 85 The back wall 55 provides an opening therein for a smoke pipe.

End panels 44 are also provided at the front end of the casing, one joined to each of the side walls 45 at their front edges. 90

A top portion C for said casing is joined to said side and rear walls and end panels, and comprises upper front and rear wall portions 46 joined by side portions 47, inclining upwardly and inwardly and providing an 95 opening in the top partially closed at its front and rear ends by top panels 48. A rectangular cold air pipe 49 extends upwardly from said top portion opening and supports a register 62 at its upper end.

Connected to the inner edges of front end panels 44 are inner side walls 63 parallel to and spaced from the outer side walls, said walls 63 extending for the full depth of the casing into engagement with the rear wall of the casing and supporting an inside top portion 59, separating the inner hot air chamber A from the cold air chamber B. The inner walls 63 are of double formation and provide a dead air space which serves as an insulation between the hot and cold air chamber. The inner walls 63 and the inner top are supported by their connection with the end panels 44 and rear wall, the walls 63 at their lower ends terminating short of the base 40 to provide communication between the space B and space A.

The inside top portion 59 is provided with a hot air pipe 60 within the cold air pipe 49 and spaced therefrom, the pipe 60 extending upwardly into a slip joint connection with a short hot air pipe 61 depending from the register 62.

The cold air enters through the register 25 and through the space between the pipes 60 and 49 and passes through the cold air space B and under each of the inner walls 63 into the hot air chamber A where the furnace unit is disposed in spaced relation to the walls of the hot air chamber A.

The ash-pit portion 20 supporting the firepot 27 of the furnace unit is slid into the furnace upon tracks 66 on the base 40 having guides 67 engaging the sides of the ash-pit.

When the furnace unit is in place, the opening in the front wall is closed by the panels 43, 41, wing plates 39 bracing the front end of the casing, the ash pit front 3 and the feed tube front 68. The wing plates 39 are secured to the panels 44 and to the base 40 to brace the same and the space between wing plates 39 is closed by the ash pit front 3.

The panels 41, preferably of galvanized iron as is the rest of the casing, are provided with flanges forming grooves 41^a on two sides for cooperation with the corresponding edges presented by the end panels 44, the feed tube front and the panel 21 interposed between the ash pit front, the panel 21 the feed tube front and also having a lower flange forming a groove 21^a for engagement with the upper edge presented by the said ash pit front. The panels 41 are provided with grooves 41^a at their lower ends engaging wing plates 39.

The upper panel 43 is provided with upper and lower flanges 43^a presenting upper and lower grooves for engagement with the edges presented by the upper side of the feed tube front, the upper ends of panels 41 and the lower end of upper front 46. Guide ribs 64 are provided on the end panels 44.

The front of the casing with the furnace in place is then completely closed, with the front panels removable. The end panels 44

are provided with flanges or clips 51 and 52 forming grooves at the top and bottom thereof to receive the edges presented by the lower end of upper front wall portion 46 and the base 40, respectively. These end panels and the remainder of the sectional casing are provided with interlocking tongue and groove connections and are provided with a few retaining bolts to prevent disconnection, thus forming a rigid casing structure with the front removed and which can be moved about independently, and tipped upon its edges without collapse or disarrangement of parts. The outside side walls 45 are provided with upper and lower clips 53 for engagement with the outside top portion and the base 40 respectively. The inside top 59 is provided with a hem 59^a at its front end turned up to receive the lower edge of front wall portion 46 of the outside top C.

The furnace unit comprises the firepot 27 and the ashpit 20 supporting the firepot and extending forwardly beyond the firepot to space the same from the sectional front wall of the furnace casing.

The ash pit 20 comprises a sheet metal box with the ashpit front 3 mounted at its front end, and ashpit frame 16 resting on top of the box and bolted to the ashpit front 3. Secured to the ashpit front 3 is ashpit door hinge 4, ashpit door catch 5, shaker lug 6, having slot 6^a therein for loosely receiving the lower end of shaker handle 19, and ashpit door 2 having draft door 1 thereon operated by chains or the like from above to regulate the air under the grate bars for combustion.

Shaker bar 23 is pivotally secured to the shaker handle 19 and extends rearwardly through the front 3 into the ashpit. The shaker handle 19 is provided with a shaker bar stop 15, pivotally secured thereto and adapted to be swung to lie on top of the shaker bar or will tip over to allow the shaker bar to slide in and out to rock the grate bars. The stop 15 when tipped to lie on top of the shaker bar provides the correct space between the shaker handle and the ashpit front to set the grate bars in level position.

The grate bars are mounted to rock in the frame 16 which comprises grate bars rests 22 bolted to the top of the ashpit. The grate bars rests have studs 22^a to rockably receive the grate bars 29 at one end of each of which is the lever arm 30 carrying a stud 30^a for engaging a corresponding aperture 23^a in the shaker bar. The lever 30 is provided with a hole 30^b to receive a stud 22^b and the opposite end of the grate bars is provided with a U-shaped notch to rest on the opposite stud 22^a. The studs 30^a of lever arms 30 of the various grate bars, of which three are shown (but any desired number, as three, four, or five grate bars may be used with furnaces the

depths of which are correspondingly varied), engage the spaced apertures 23^a in the shaker bar to be rocked thereby.

The firepot is bolted to the firepot frame

5 18 and is supported thereon. Frames 16 and 18 are bolted together through lugs 70. The feed tube 7 extends forwardly from the firepot and spaces the same from the front wall of the casing. The feed tube has a flange 71 thereon engaging the outside of the front wall 26 of the firepot at the feed opening and a collar 13 on the inside of the wall 26 bolts through the flange 71 and holds it to the firepot.

10 15 The feed tube front 68 comprises a feed door hinge member 11 secured to the right side of the open mouth of the feed pouch, a feed door catch member 12 secured to the left side of the feed tube mouth, upper and 20 lower sheet iron flanges 38 and 28 connecting 11 and 12, and a door 8 provided with a cold air draft 9.

15 The door 8 is provided with a feed door lining comprising a plate 10 having a rearwardly extending flattened hot blast tube 10^a subject to the heat in the firepot to preheat the cold air entering through draft door 9 operated through eye 9^a by chains from above.

20 At the inside end of the feed pouch is a feed pouch apron 14 to hold the front bricks E in place. This apron is bolted to the bottom of the feed tube and has a depending inner flange 14^a overlying and protecting the top ends of the fire bricks.

25 35 Bricks F, larger and longer than the front bricks E are disposed at the sides and back of the firepot. All of the bricks are supported upon the firepot frame 18. Casting 35 is disposed at the rear wall of the firepot and has 40 a depending flange 35^a to overlie and hold the bricks in place. Castings 36 at the sides of the firepot protect and hold the side bricks in place.

30 45 In the smoke opening in the rear wall 25 of the firepot is mounted a smoke collar 32 having a flange 32^a engaging the outside of the rear wall. The smoke collar projects inwardly of the wall 25 and receives on its inner end a smoke collar ring 33 bolted to the inner face of the wall 25 and an elbow 34 attached to the inner end of the smoke collar by means of pins. The elbow 34 is preferably made in two parts bolted together and is disposed with its open end up to receive the smoke accumulating in the curved dome 27^a of the firepot. On the outer end of the smoke collar is secured smoke collar extension 37 which preferably hooks on the collar with hook bolts and extends through the back wall 55 of the casing to connect to the usual smoke pipe.

40 45 A water pan 58 is mounted for slidable application and removal on the rear face of the left panel 41 and panel 41 is provided with an opening 41^b having a swinging cover enabling 65 the filling of the water pan. A brace 65 ex-

tends across the cold air chamber between the inner and outer side walls.

The inside top 59 is preferably lined with asbestos.

70 My furnace is designed to provide standard parts so far as the width of the furnace is concerned and to provide for changing the depth of the furnace from front to rear without altering the width of the furnace.

75 Thus furnaces having two, three, four, or five grates may be provided having different depths from front to rear, but the width of the parts remaining standard.

80 A standard set of removable panels for the front of the casing is applicable to all depths of furnaces made according to my invention. The front panels are removable to permit the removal of the firepot and ashpit without the use of any tools. The side walls of the casing are made in different lengths for 85 the different depths of furnaces according to the number of grates used. The back of the casing is standard for all sizes of furnaces. The casing being composed of sections of 90 sheet metal such as galvanized iron or the like, it may be said generally that the front and rear parts or sections are standard and the side portions are varied according to the number of grates used, thus enabling the production of a large number of standard parts for 95 all sizes of furnaces.

100 The coal furnace is made in three different styles of casing; i.e., the pipeless furnace casing shown in the drawings, the pitless casing, which is used for pipe jobs, and the regular casing.

105 A pitless casing embodying features of my invention including the three removable panels and removable furnace features is shown in Fig. 22.

110 The pitless furnace casing provides hot air outlet pipes 100 at the top and cold air return pipes 101 at the sides connecting with cold air closed top casings 102 which admit cold air to the hot air chamber 103 which removably receives the furnace 104. The removable panels are shown at 105, 106 and 107.

115 The regular furnace casing embodies the same three panels and removable furnace features of my invention but differs from the pipeless furnace casing shown, in that all of the end panels 44 are removed, front and back, and the outside sides 45 take the place of the inside sides 63, and the guide 64 is connected directly to the outside sides 45.

120 The novel form of front and back construction provided by my invention thus controls the whole casing assembly for all styles of casing.

125 The feed door assembly on the furnace, the front end of the firepot, the back end, the smoke collar assembly, and the ash pit assembly front and back ends, are the same in all sizes of furnaces.

To make the next size of furnace, it is only necessary to provide a corresponding length of grate rest 22, bottom side of firepot frame 16, castings 36 to go on top of side firebricks, 5 a firepot cover 27 providing sides and curved top, an extra grate and two extra firebricks, one on each side. The other parts of the furnace are standard. Everything pertaining to the width of the furnace back and front 10 ends is standard.

I do not wish to limit myself to the exact structure shown in the drawings and particularly described as it will be understood that many modifications may be made within the 15 scope of the invention.

The pipeless furnace shown is adapted for the burning of coal.

While Fig. 22 shows a wood burning furnace within the pitless casing, the pitless casing 20 is equally adaptable to receive a coal furnace such as shown in Fig. 1 and throughout the other figures of the drawings.

Certain subject matter disclosed in this application is contained in my co-pending 25 divisional application, Ser. No. 446,772.

I claim:

1. In combination in a furnace, an independent self-supporting casing comprising side walls and a rear wall joining the side 30 walls, a top portion having an opening therein and connected to the side and end walls, inner side walls spaced from said side walls and forming therebetween a hot air chamber for receiving a furnace unit, end panels closing 35 the space between the ends of each pair of inner and outer side walls, and a cover portion for said hot air chamber connected to the inner side walls and having an opening registering with said first mentioned opening, the 40 front end of said hot air chamber being open to receive the furnace unit.

2. A furnace according to claim 1 in which said top portion of the casing has vertical end walls and horizontal top panels and inclined 45 side walls forming said opening, a cold air pipe mounted on said top portion in registration with said opening, a register mounted on said cold air pipe, a hot air pipe mounted on top of said cover portion for the hot air 50 chamber and extending upwardly within the cold air pipe and spaced therefrom into engagement with a relatively short hot air pipe depending from the said register.

3. A furnace according to claim 1 in which 55 the rear wall of the casing is provided with an opening for the smoke pipe, a base for said furnace casing and furnace unit comprising a framework of angle iron, and panels for closing the front end of the hot air casing including an upper front panel above the furnace feed tube, intermediate panels below the upper panel and at the sides of the furnace feed tube between the latter and the end panels 60 of the casing, a spacer panel between the feed tube and the ash pit front of the furnace 65

and between said intermediate panels, and wing plates at each side of the ash pit front secured to the base and to the casing to brace the same, said panels and casing being interconnected by tongue and groove connections, and said panels being provided with handles to facilitate connection and disconnection thereof. 70

4. In a furnace, a sectional casing providing an air inlet and outlet and a furnace unit for reception within said casing in spaced relation thereto, the open front of said casing being closed, in part by the ashpit front and feed tube front of the furnace unit and in part by removable sheet metal sections having 75 interfitting tongue and groove connections with the casing and with the flanges of the ashpit and feed tube fronts.

5. In combination in a furnace having an independent furnace unit removable as a unit from an independent casing, said casing comprising an upstanding main portion having side walls, end panels at each side joining to each side wall at the front and rear extremities thereof and extending inwardly therefrom, front and back upper wall portions joining the tops of said front and rear end panels and in the planes thereof, said upper wall portions having inwardly and upwardly inclined side edges, shoulder portions co-extensive with and joining the tops of the side walls and inclining upwardly against said side edges, transverse horizontal top panels at the front and rear of said casing and joining said opposite inclined shoulder portions and extending inwardly from the tops of the said upper wall portions, the inner edges of said top panels and the top edges of said inclined shoulder portions forming a rectangular opening, inner side walls supported at the inner side edges of the said end panels and in spaced parallel relation to said outer side walls and terminating short of the lower edges of the outer side walls, a rear wall connecting the inner side edges of the opposite rear end panels and forming with the inner side walls a hot air chamber for receiving a furnace unit, a cover portion for said hot air chamber connected to the inner side walls and having an opening in spaced registry with said first mentioned rectangular opening, a cold air pipe mounted on said casing at said rectangular opening, and a hot air pipe mounted on said cover portion of the hot air chamber at the opening therein, 100 said hot air pipe extending upwardly within and spaced from said cold air pipe; said inner side walls forming with the outer side walls cold air inlet passages at the sides only of said casing, a base for said furnace casing and unit and readily removable panels for closing the front end of the hot air casing with the furnace unit in place. 105

6. In a furnace according to claim 5, readily removable panels for closing the front 110

end of the hot air casing with the furnace unit in place, including an upper front panel above the furnace feed tube, intermediate panels below the upper panel and at the sides 5 of the furnace feed tube between the latter and the end panels of the casing, a spacer panel between the feed tube and the ash pit front of the furnace and between said intermediate panels, wing plates at each side of the ash pit front secured to the base, said 10 panels and casing being interconnected by tongue and groove connections, the said end panels being provided with flanges or clips forming grooves at the top and bottom thereof to receive the edges presented by the lower 15 end of the upper front wall portion and the base, guide ribs extending inwardly from the connection of the front end panels to the inner side walls; said upper front panel having upper and lower flanges presenting upper 20 and lower grooves for engagement with the edges presented by the lower end of the upper front wall, the upper side of the feed tube front, and the upper ends of the intermediate panels; said intermediate panels 25 having flanges forming grooves on each side and at the bottom for engaging the side edges presented by the guide rib of the end panels, the feed tube front, the spacer panel, and the 30 upper edge of the wing plates; said spacer panel having a lower flange forming a groove for engaging the upper edge of the ash pit front, the upper edge of the spacer panel resting against the front of the lower edge of 35 the feed tube front, said removable panels being provided with handles to facilitate connection and disconnection thereof, said furnace casing having all parts pertaining to the width thereof, of standard size for all 40 sizes of furnaces, one of said removable intermediate panels being provided with a water receptacle on its inner side, an opening in said panel for filling the water receptacle and a pivoted cover for the opening.

7. In a furnace according to claim 5 said 45 rear wall, and inner side walls comprising double sheet metal walls comprising double sheet metal providing dead air spaces, the double formation of the inner side walls providing a dead air space which serves as an 50 insulation between the hot and cold air chambers, said outside side walls being provided with upper and lower clips forming grooves for engagement with the lower edges of the 55 said shoulder portions of the outside top and an upper edge on the base, said inside side walls having upper clips forming grooves to receive the inside top or cover portion for the 60 hot air chamber, said horizontal top panels and top edges of the inclined shoulder portions being provided at said rectangular opening with flanges forming grooves to receive the lower edge of the cold air pipe, said 65 inside cover portion at its front end having

a hem turned up to receive the lower edge of the front upper wall portion of the outside top.

In testimony whereof, I affix my signature.

SAMUEL DANIELS.
